DESIGN FOR A TOP FOR A GAME TABLE OR SIMILAR ARTICLE

Application filed January 14, 1933. Serial No. 46,830. Term of patent 3½ years.

To all whom it may concern:

Be it known that I, CARL F. KLEIN, a citizen of the United States, residing at Chicago, county of Cook, and State of Illinois, have invented a new, original, and ornamental Design for a Top for a Game Table or Similar Article, of which the following is a specification, reference being had to the accompanying drawing, forming a part thereof, wherein—

The figure is a perspective view of a top for a game table, showing my new design.

I claim:

The ornamental design for a top for a game table or similar article, as shown.

CARL F. KLEIN.
